UNITED STATES PATENT OFFICE.

JACOB R. HESSLER, OF CHICAGO, ILLINOIS, ASSIGNOR TO THE W. W. KIMBALL COMPANY, OF SAME PLACE.

CABINET-ORGAN SOCKET-BOARD.

SPECIFICATION forming part of Letters Patent No. 369,938, dated September 13, 1887.

Application filed May 31, 1887. Serial No. 239,766. (No model.)

To all whom it may concern:

Be it known that I, JACOB R. HESSLER, a citizen of the United States, residing in Chicago, in the county of Cook and State of Illinois, have invented a new and useful Improvement in Cabinet-Organ Socket-Boards, of which the following is a specification.

The horizontal reed-cells of cabinet-organs as now generally constructed are cut or hollowed out from the under side of what are known as the "socket-boards." They are short rectangular openings, ranging in length from five-eighths of an inch to about four inches, and are nearly square in vertical cross-section. The vertical sides of the cells are straight and parallel surfaces, and the same is true of the upper and lower sides. As thus constructed, the organs now manufactured are very superior instruments, and although efforts have been made in various ways to render them more sonorous—one such effort consisting in arching the roof of the cells longitudinally, the apex of the arch being about midway of the length—such efforts have, so far as my knowledge extends, been universally abandoned in favor of the straight uniform cells. It is to the latter that my invention relates, and I have discovered a construction of socket-board which, while it need not increase the cost of manufacture, greatly augments the power of the tone without otherwise changing it in any respect; and it consists in a socket-board the horizontal reed-cells whereof differ from the straight uniform cells described in that the roofs are inclined upward from the inner end to the mouth, thus not only giving additional freedom of egress to the sound-waves, but also causing the top of the cell to act as a reflector of sound. In this change I preferably lower the roof at the inner end of the cell from the common construction and elevate it at the mouth, and thus am able to obtain the benefits of the invention without increasing the thickness of the socket-board, care being taken that the roof be not so low as to interfere with the vibration of the tongue of the reed. No harm will be done, however, by adding to

the thickness of the board, as that permits an increase of the angle of the incline of the 5c cell-roof. I estimate that the power of the instrument is nearly doubled by my invention, so that a small instrument can be made effective where a large one has heretofore been required.

In the accompanying drawing I have shown a transverse vertical section of my invention, and in such drawing A represents the socket-board, B the sounding-board, and C the reed.

D is one of the reed-cells and a type of all 60 of them, a being the side, b the bottom, c the inner end, and d the mouth thereof. The top or roof e is a straight plane surface without openings therethrough to give egress to the sound or obstructions of any kind to detract 65 from its power, and inclines upwardly and outwardly from the inner end, as plainly illustrated, while in other respects the cell is like the common construction. The angle of incline is a matter of discretion, and the benefits 70 of my invention may be obtained without increasing the height of the socket-board beyond the ordinary thickness by lowering the inner and elevating the outer ends of the roof. The inner end may be lowered to any 75 extent permitted without interfering with the vibrations of the reed-tongue f, the upper extent of which vibration may be indicated by the dotted line. The incline extends clear to the open end of the cell, so that the sound is 80 not interfered with or confined in any way.

I am well aware, of course, that it is common to provide horns and other wind-instruments with flaring rims at the mouths for the purpose of increasing the tone effect; but I 85 am not aware that a reed-cell or other short analogous chamber has been provided with an inclined top extending from the inner to the outer end without openings through which the sound-waves will be diverted, or obstructions at the mouth whereby the character of 90 the tone will be changed and some portion of the power lost. The dotted line extending along the top of the cell shows the roof as it has heretofore been customarily made.

I claim—

55

60

65

70

75

80

95

The socket-board the reed-cells whereof are horizontal, contain but a single reed each, are uniform in shape, and are provided with roofs inclining continuously in an upward direction 5 from the inner end to the extreme mouth or outer end, said roofs having no openings therethrough, and the mouths being wholly

free from obstructions to hinder the sound or affect its character, substantially as set forth.

JACOB R. HESSLER.
